(57) **CLAIM**

The ornamental design for a cabinet with dehumidifier, as shown and described.

DESCRIPTION

1. Cabinet with dehumidifier

1.1 : Perspective

1.2 : Front

1.3 : Back

1.4 : Left

1.5 : Right

1.6 : Top

1.7 : Bottom

1.8 : Perspective

1.9 : Front

1.10 : Back

1.11 : Left

1.12 : Right

1.13 : Top

1.14 : Bottom

The broken lines depict portions of the cabinet with dehumidifier that form no part of the claimed design; the dash-dot broken lines define the boundary of the claimed design and form no part thereof; reproduction 1.1 is a front perspective view of the cabinet with dehumidifier; reproduction 1.8 is a front perspective view thereof in a condition that the dehumidifier is in operation; reproductions 1.2 and 1.9 are front views of reproductions 1.1 and 1.8, respectively; reproductions 1.3 and 1.10 are back views of reproductions 1.1 and 1.8, respectively; reproductions 1.4 and 1.11 are left views of reproductions 1.1 and 1.8, respectively; reproductions 1.5 and 1.12 are right views of reproductions 1.1 and 1.8, respectively; reproductions 1.6 and 1.13 are top views of reproductions 1.1 and 1.8, respectively; and reproductions 1.7 and 1.14 are bottom views of reproductions 1.1 and 1.8, respectively.

1 Claim, 14 Drawing Sheets
